United States Patent Office.

SAMUEL BRILLINGER, OF CLARENCE CENTRE, NEW YORK.

Letters Patent No. 89,849, dated May 11, 1869.

IMPROVEMENT IN PUMPS.

The Schedule referred to in these Letters Patent and making part of the same.

To all whom it may concern:

Be it known that I, SAMUEL BRILLINGER, of Clarence Centre, in the county of Erie, and State of New York, have invented certain new and useful Improvements in Pumps; and I do declare that the following is a full and exact description thereof, reference being had to the accompanying drawings, making a part of this specification, in which—

Figure 1 is a side elevation, showing the outer cylinder in section, and part of the inner cylinder broken away.

Figure 2 is a plan.

Figure 3, a section of the cylinder in line of *x x*, showing position of ports, &c.

Like letters of reference indicate corresponding parts in all the figures.

The object of my invention is to provide a double-acting pump without using valves, and consists essentially in employing a rock-chamber, in a cylinder or case, provided with suitable ports, and combining therewith a reciprocating piston for receiving and expelling the water, as hereinafter set forth.

In the drawings—

A represents the outer cylinder, or case, the hollow interior of which is conical, enclosing a similar cone-shaped chamber, *B*, which packs closer by being pushed or worked further in, when, by constant friction, it wears away. To lessen this friction of the chamber, which works with a transverse rocking motion, I hollow out a section of the centre, leaving an annular space all around between it and the case, shown at *b b*.

This chamber is provided with two induction and two ejection-ports, or holes *c c'*, representing the upper, and *d d'* the lower ones. (See figs. 1 and 3.)

C and *D* represent two water-passages, or pipes, arranged parallel to the case *A*, and united therewith by elbow-pipes *e f g h*.

These pipes work in connection with the four ports *c c', d d'*, in the chamber *B*, as will be hereinafter explained.

E represents the plunger, or piston, and *i*, the rod, the latter having a direct action by means of forked arm *F*, which is connected with crank *L*.

This rod is fastened to a cross-piece, *j*, and runs through guide *k*.

It works through stuffing-box *G* and head of chamber *B*, in which the plunger works.

In order to get the rocking motion of the chamber *B*, I attach an arm, *H*, to the head of said chamber.

This is pivoted to another arm *I*, which is attached to the end of a long forked rock-lever, *J*.

This lever is supported by a fulcrum, *K*, and its forked ends enclose the crank-pin *n*, which, in its revolutions, produces the desired rocking motion, the arrangement of which is clearly shown in the drawings.

This action turns the chamber *B*, and thereby brings

its ports in the right position to receive and discharge the water at the exact moment, as the plunger reciprocates.

The crank-pin, therefore, does not act eccentrically, but works exact, striking the inside of the forks of lever *J* at the exact moment to raise and depress said lever, and thereby move the rock-chamber with entire precision.

The operation is as follows:

As the piston *E* is forced down, as shown in fig. 2, the chamber *B* is half turned, bringing the hole *c* opposite elbow-port *g* and hole *d*, on the opposite side and end of piston to opening of elbow *h*. Therefore, the water is sucked in through main pipe *o* into pipe *C*, thence through elbow *g* into the chamber *B*, and the water already in said chamber, by a downward action of the plunger, is forced out of hole *d* into elbow *h*, thence through passage *D*, out through ejection-pipe *p*. As the plunger is drawn back, the chamber *B* is immediately half turned, and the action is exactly reversed, thus producing a double action.

The essential principle in this pump, it will be noticed, is the combination of the rock-chamber *B* and reciprocating plunger *E*, the former taking the place of valves by alternately opening and closing the ports, and the latter simply drawing and expelling the water. This combination I believe to be new.

I am aware that double-acting pumps are common, but I believe that my method of producing the result is novel, and from its peculiar arrangement possesses many advantages over other pumps. Besides saving in packing, and working without valves, it is less liable to clog than any pump I am acquainted with. It will work through dirt, and even sawdust, without clogging, which valve-pumps cannot do.

It will be valuable, I am satisfied, for any work that pumps can be put to, but it is peculiarly adapted for steam-engines, for reasons above stated. It will work in any desired position, either horizontal or vertical.

What I claim as my invention, and desire to secure by Letters Patent, is—

The combination and arrangement, with cylinder *A*, having side-passages *C D*, of the rock-chamber *B*, provided with ports *c d* and reciprocating plunger *E*, the whole operating in the manner and for the purpose specified.

Also, the combination and arrangement, with rock-chamber *B* and plunger *E*, of the forked lever *J*, arms *H I*, and the lever *F*, operating as described, and for the purpose hereinafter specified.

In witness whereof, I have hereunto signed my name, in the presence of two subscribing witnesses.

SAMUEL BRILLINGER.
